WATER COOLER

Robert R. Fink, Chicago, Ill., assignor to General Electric
Company, a corporation of New York

Filed Aug. 29, 1960, Ser. No. 61,923

Term of patent 14 years

(Cl. D67—4)

FIG. 1

FIG. 2

FIG. 3

Fig. 1 is a front perspective view of a water cooler showing my new design;

Fig. 2 is a rear perspective view thereof; and

Fig. 3 is a top plan view thereof.

The side of the device not shown by the drawing is essentially the same as the side shown.

What is claimed is:

The ornamental design for a water cooler, substantially as shown and described.
